UNITED STATES PATENT OFFICE.

FREDERIC E. BERTRAND, OF LYNN, MASSACHUSETTS, ASSIGNOR TO UNITED SHOE MACHINERY CORPORATION, OF PATERSON, NEW JERSEY, A CORPORATION OF NEW JERSEY.

THREAD-WAXING DEVICE.

Application filed March 22, 1919. Serial No. 284,466.

To all whom it may concern:

Be it known that I, FREDERIC E. BERTRAND, a citizen of the United States, residing at Lynn, in the county of Essex and State of 5 Massachusetts, have invented certain new and useful Improvements in Thread-Waxing Devices; and I do hereby declare the following to be a full, clear, and exact description of the invention such as will enable 10 others skilled in the art to which it appertains to make and use the same.

This invention relates to thread waxing devices for sewing machines.

The wax ordinarily employed in waxing 15 sewing thread, which is solid at ordinary temperatures and is reduced to a fluid state by the application of heat thereto before it is applied to the thread, deteriorates rapidly in quality when maintained at the 20 high temperature required to enable the wax to permeate properly the thread. In thread waxing devices in which a relatively large body of wax is maintained at a high temperature for a long time, much of the wax 25 deteriorates in quality before it is used.

One of the principal objects of the present invention is to produce a thread waxing device of novel and improved construction in which such deterioration in the quality of 30 the wax will be avoided.

With this object in view an important feature of the invention consists in the provision of an atmospheric pressure controlled or so-called barometric feeding reservoir arranged to supply wax to the chamber or receptacle in which the wax is applied to the thread. Such an arrangement permits the use of a receptacle of relatively small capacity in which the wax is applied to the thread 40 and a reservoir of relatively large capacity for replenishing the supply in the waxing receptacle. The heating devices are arranged to heat the wax in the receptacle to a relatively high temperature to maintain the same in proper condition to be applied 45 to the thread and to heat the wax in the reservoir to a relatively low temperature so as to melt the same gradually as required to replenish the wax in the receptacle.

Another feature of the invention contemplates the provision of means for removably supporting a supply reservoir in operating position with relation to the thread waxing chamber so that the reservoir may be re-

moved when the wax is exhausted therefrom 55 and another reservoir full of wax substituted therefor.

Another feature of the invention contemplates the provision of two supply reservoirs and means for supporting the same so that they may be alternatively located in operating position with relation to the waxing receptacle. Thus while one reservoir is placed in operating position with relation to the receptacle, the other constitutes a reserve 65 reservoir which may be used when the wax in the first reservoir is exhausted.

Still another feature of the invention contemplates the provision of supporting devices for the reservoirs of such construction 70 and arrangement that when one reservoir is in operating position, the reserve reservoir receives a certain amount of heat from the heating devices so that it is ready for immediate use when the wax in the first reservoir 75 is exhausted.

Other objects of the invention are to improve the construction and mode of operation of thread waxing devices, and to produce a thread waxing device in which the 80 supply of wax may be much more easily and conveniently renewed than in such devices heretofore constructed.

In the present construction the supply reservoir comprises a support or holder especially constructed to receive cartons of paper or cardboard filled with hard wax. In order to render the cartons unfit to be used again, means is provided for mutilating the cartons. To insure the mutilation 90 of the cartons before they are removed from the device, retaining means is provided which will prevent the removal of the cartons from the device until the mutilating means is actuated to mutilate the same. 95

Other features of the invention consist in certain novel and improved constructions and combinations of parts hereinafter described and particularly pointed out in the claims the advantages of which will be 100 understood and appreciated by those skilled in the art.

The various features of the invention will be readily understood from the accompanying drawings illustrating the invention in 105 its preferred form, and the following detailed description of the constructions therein shown.

In the drawings Figure 1 is a plan view of a thread waxing device embodying the invention; Fig. 2 is a view of the device partly in front elevation and partly in section on the line 2—2 of Fig. 1; Fig. 3 is a view in side elevation of the device; Fig. 4 is a sectional view of the device taken substantially on the line 4—4 of Fig. 1; Fig. 5 is a fragmentary sectional view taken on the line 5—5 of Fig. 1; and Fig. 6 is a fragmentary sectional view taken on the line 6—6 of Fig. 5.

In the drawings the thread waxing chamber or receptacle through which the thread is passed on its way from the supply to the work is indicated at 10, and consists of a shallow trough of relatively small capacity in which the wax is maintained in a thoroughly melted state by the heat transmitted from a steam chamber 12 formed in the wall of the receptacle. Two wax supply reservoirs are illustrated in the drawing, these reservoirs being indicated respectively at 14 and 16. These reservoirs are of the same construction and each consists of a support or holder 18 formed at its upper end with a relatively large recess or chamber and a passage-way leading downwardly from said chamber through a discharge nozzle 20 formed at the lower end of the holder, and a carton 22 mounted in the chamber in the upper portion of the holder. The carton is closed at its upper end and is open at its lower end and is preferably constructed of heavy paper or cardboard. The holders 18 are each provided with a hinged cover 24 arranged to engage the upper end of the carton to hold the same securely in place in the holder. Both reservoirs are removably mounted side by side on a slide 26 mounted to slide over a shelf 28. The slide 26 is adapted to be shifted over the shelf 28 by means of a handle 30 secured to one end of the slide. The slide 26 is provided with two openings 32 extending through the slide into which the nozzles of the supply reservoirs are inserted. As illustrated in the drawing the reservoir 14 is located in operating position in communication with the thread waxing chamber 10, while the reservoir 16 is located in inoperative position out of communication with said chamber and constitutes a reserve reservoir. The body of the holder 18 of the reservoir, which is in position to supply wax to the chamber 10, rests on the slide 26 and the nozzle of the reservoir extends through one of the openings 32 in the slide and through the corresponding opening 34 in the shelf 28 and projects slightly into the chamber 10 so that the opening at the lower end thereof is sealed or covered by the melted wax in said chamber when the chamber is filled with wax. The nozzle of the reserve reservoir is inserted in the other opening 32 in the slide 26 and rests

upon the shelf 28, which supports the reservoir with the body of the holder 18 out of contact with the slide, and also closes the lower end of the nozzle, thereby preventing the wax in the reserve reservoir from being discharged through the nozzle. 70

In order that the carton 22 and the holder 18 when associated may be employed as barometric feeding reservoir, provision is made for forming an air-tight joint between the open end of the carton and the holder. This is accomplished by providing an interior shoulder 36 having a tapering surface at the lower portion of the body of the holder upon which the open end of the carton may rest. When the cover 24 is closed the carton is pressed firmly against the tapering surface of the shoulder so that air is prevented from entering the reservoir except through the nozzle 20. The wax in the reservoir is kept at the proper temperature by means of a steam chamber 38 formed in the frame of the device adjacent the slide 26. The heat transmitted from the steam chamber 38 is sufficient to maintain the wax in a fluid condition in the nozzle and lower portion of the reservoir which is in use. As long as the supply of wax in the chamber 10 is above the lower end of the nozzle of this reservoir it closes the opening in the nozzle against the entrance of air, and no wax will flow from the reservoir into the chamber 10. As the wax in the chamber 10 is used up to the point where its surface falls below the lower end of the nozzle, air is permitted to enter the reservoir and the wax will flow from the reservoir into the chamber 10 until the lower end of the nozzle is again closed. In this way a substantially uniform quantity of wax is maintained in the thread waxing chamber. The wax in the upper part of the reservoir is softened somewhat by the heat transmitted thereto, and will flow gradually downward to the nozzle of the reservoir as the wax is discharged through the nozzle. The reserve reservoir becomes heated to a relatively slight degree inasmuch as the body of the holder 18 of the reserve reservoir is held out of contact with the slide 26 through the engagement of the lower end of the nozzle with the shelf 28. It is also to be noted that the portion of the frame of the device in which the steam chamber 38 is formed does not extend to a point opposite the position of the reserve reservoir so that the temperature of the slide 26 at the point where the reserve reservoir is supported is somewhat less than at the point where the active reservoir rests on the slide. The temperature of the reserve reservoir, however, is sufficient to soften the wax therein so that this reservoir is ready for use when the wax in the reservoir which is being used is exhausted. In replacing an exhausted reservoir with a reserve reservoir, the 130

former is lifted sufficiently to raise the nozzle 20 of said reservoir above the surface of the shelf 28, and the slide 26 is then shifted to bring the reserve reservoir into position for the insertion of the lower end of the nozzle through the opening 34 in the shelf. It will be apparent that the slide 26 is locked in position on the shelf 28 when either of the reservoirs is in operating position by the engagement of the nozzle of the active reservoir in the respective openings in the slide and shelf.

With a thread waxing device of the above construction, only a relatively small quantity of wax is heated to a high temperature at any time, the main body of the wax in the device being kept relatively cool. The wax, therefore, is maintained at a high temperature for only a short time before it is applied to the thread, and consequent deterioration of the wax is avoided.

It may be desirable for certain reasons to prevent the cartons employed in the present device, after having been used, from being refilled and used again, and to this end means is provided for mutilating the cartons before they are removed from the device. In the present construction the mutilating means comprises a punch 40 which is carried by the cover 24 and is arranged to be projected through a slot 42 in the holder 18 into the carton near the closed end thereof before the removal of the carton from the holder. In order to insure that the punch will be inserted in the carton before the carton is removed from the holder, a latch 44 is provided for latching the cover in closed position, which is arranged to be released by the mechanism for actuating the punch and cannot be released without first actuating the punch. The latch is mounted to slide in the cover 24 and is arranged to engage at its forward end beneath one or more shoulders 46 formed on the holder 18. The latch is arranged to be projected into latching position by means of a coiled spring 48. The punch 40 is carried by an arm 50 fixed to one end of a slide bar 52 mounted to slide longitudinally through a bearing in the cover. The opposite end of the slide bar 52 is pivotally connected at 54 with a handle 56. The handle 56 and the cover 24 are both pivoted on the holder 18 by means of a pin 58, and the handle is connected with the cover 24 by means of a spring 60. The spring 60 tends to pull the handle 56 toward the cover, thereby holding the slide bar 52 in the position shown in Fig. 5, with the punch 40 clear of the carton. The means for releasing the latch 44 consists of a lug 62 mounted on the punch carrying arm 50, which is arranged to be projected through the slot 42 so as to engage the forward end of the latch just before the punch reaches the limit of its inward movement, and

pushes the latch back out of engagement with the shoulders 46 on the holder.

When it is desired to remove an empty carton from one of the holders 18, the operator swings the handle 56 in the direction of the arrow, (Fig. 2), drawing the slide bar 52 through its bearings in the cover, and thus moving the punch carrier 50 inwardly toward the holder 18 so that the punch penetrates the side of the empty carton and the lug 62 releases the latch 44. After the release of the latch the cover is swung upwardly by the continued movement of the handle 56. The punch 40 is swung upwardly with the cover by the action of the spring 60 and the carton is raised so that it projects above the holder 18 and may be easily grasped by the operator and removed from the holder.

When a carton full of wax is inserted in the holder 18 and the cover is swung into closed position, the cover engages the upper end of the carton and forces the same downwardly, thereby pressing the lower end of the carton firmly against the shoulder 36 on the holder to form an air tight joint between the lower end of the carton and the holder. In the illustrated construction the under side of the cover is so shaped as to enter into the top of the holder 18, as clearly shown in Figs. 2 and 6.

The thread guiding and stripping means comprises a pulley 64 and a stripping device 66, both of which are carried by an arm 68 pivotally mounted on a shaft 70, supported by projections 72 and 74 formed on the side of the receptacle 10. The arm 68 is arranged to be normally supported on the shaft 70 with the thread guide and stripping device in their operative positions, as shown in full lines in Fig. 4, and is adapted to be swung upwardly and supported in the position shown in dotted lines in said figure so that the parts may be easily accessible for the purpose of threading.

The thread guiding pulley 64 is journaled on a stud 76 mounted on a depending portion of the arm 68, and when in its normal or operative position the pulley is located adjacent the bottom of the thread waxing chamber 10, and close to the steam chamber 12 where it is immersed in the hottest part of the melted wax. The thread in its passage through the thread waxing chamber extends downwardly through a passage 78 in the arm 68, thence under the pulley 64 and upwardly through the stripping device 66.

The stripping device comprises the usual rubber stripper block 80 which is provided with an axial passage for the thread. The stripper block is held in a cup 82 provided with a hollow stem 84 which is secured by means of a set screw in a socket formed in the arm 68. The cup 82 is externally

threaded at the top to receive a cap 86 and a follower plate 88 is interposed between the cap and the stripper block.

In order that the thread guide and stripper may be supported either in operative position or in threading position, the arm 68 is provided with a laterally extending lug 90 arranged to engage the projection 74 to hold the arm 68 in position. The lug 90 is formed with a beveled inner face to engage a correspondingly beveled surface 92 formed on the upper end of the projection 74 to hold the arm 68 and the parts carried thereby in operative position, and is also arranged to engage the outer face 94 of said projection to hold the arm 68 and said parts in threading position. To enable the lug 90 to be disengaged from the projection 74, and the arm 68 to be swung about the shaft 70 from one position to another, the arm is mounted to slide longitudinally on the shaft 70 and is acted upon by a coiled spring 96 which normally holds the arm in position on the shaft with the lug 90 in engagement with one of the cooperative surfaces of the projection 74. The lug 90 may be moved out of engagement with the projection 74 by moving the arm 68 longitudinally of the shaft 70 against the action of the spring 96, and the arm may then be swung about the shaft from one position to another. After the arm is swung into the desired position and allowed to be moved by the spring, the spring will force the arm laterally to carry the lug 90 into cooperative position with relation to one of the contact faces of the projection 74. When the arm 68 is in operative position the beveled face of the lug 90 is forced against the inclined surface 92 of the projection 74 by the spring 96 so as to accurately position the arm 68 and prevent any vibrations thereof.

As implied in the foregoing description the invention is not limited to the specific construction of the illustrated embodiment thereof but may be modified in form and in minor details without departing from the spirit and scope of the appended claims.

Having described the invention, what is claimed is:

1. A thread waxing device for sewing machines having, in combination, a thread waxing chamber, a barometric feeding reservoir arranged to supply wax to said chamber, and heating devices arranged to maintain the wax in said chamber in a liquid condition and to melt the wax in said reservoir only as required to replenish the wax in the receptacle.

2. A thread waxing device for sewing machines having, in combination, a thread waxing chamber, a closed reservoir having a discharge extremity projecting into said chamber for automatically replenishing the

supply of wax in the chamber, means for heating the wax in the chamber, and means for heating the wax in the reservoir.

3. A thread waxing device for sewing machines having, in combination, a thread waxing chamber and a closed reservoir, having an open discharge nozzle removably mounted in position with relation to the chamber with the nozzle extending into the chamber so that the wax in the chamber will close the opening in the nozzle and that the wax will be delivered from the reservoir to the chamber on the barometric feeding principle as the wax is exhausted from the chamber. 70 75 80

4. A thread waxing device for sewing machines having, in combination, a thread waxing chamber, two wax supply reservoirs and means for supporting the reservoirs so that they may be alternatively located in operating position with relation to the waxing chamber. 85

5. A thread waxing device for sewing machines having, in combination, a thread waxing chamber, two wax supply reservoirs, means for supporting the reservoirs so that they may be alternatively located in operating position with relation to the waxing chamber, and heating devices arranged to maintain the wax in the receptacle in a liquid condition, to melt the wax in the reservoir in operating position gradually as required to replenish the wax as it is exhausted from the thread waxing chamber, and to heat the wax in the reserve reservoir to a slight degree so that said reservoir will be ready for use when placed in operating position. 90 95 100

6. A thread waxing device for sewing machines having, in combination, a thread waxing chamber, a support, and one of a plurality of holders each adapted to be interchangeably mounted on said support and to receive and confine a wax containing carton in such a manner as to provide a barometric feed reservoir arranged to deliver wax to said chamber. 105 110

7. A thread waxing device for sewing machines having, in combination, a thread waxing chamber, a shelf having an opening extending therethrough communicating with the chamber, a slide mounted on the shelf and having openings therein arranged to be brought alternatively into registration with the opening in the shelf by the movement of the slide, a reservoir having a discharge nozzle removably mounted on the slide with its nozzle extending through one of the openings in the slide and through the opening in the shelf into the thread waxing chamber, and a similar reserve reservoir removably mounted on the slide with its discharge nozzle extending through another of the openings in the slide and resting on the shelf. 115 120 125

8. A thread waxing device for sewing ma- 130

- chines having, in combination, a thread waxing chamber, a slide and two wax supply reservoirs mounted on the slide and arranged to be located alternatively in operating position with relation to the chamber by the adjustment of the slide.
9. A thread waxing device for sewing machines having, in combination, a thread waxing chamber, devices for guiding the thread through the chamber, a shelf having an opening extending therethrough and communicating with the chamber, a slide mounted on said shelf and having openings therein arranged to be placed alternatively in registration with the opening in said shelf by the movement of the slide, a wax supply reservoir having a discharge nozzle removably mounted on the slide with its nozzle extending through one of the openings in the slide and through the opening in the shelf into the waxing chamber, a similar reservoir removably mounted on the slide with its nozzle extending through another of the openings in the slide and resting on the shelf, a heating device arranged adjacent the thread guiding devices, and a second heating device arranged adjacent the opening in the shelf.
10. A thread waxing device for sewing machines having, in combination, a thread waxing chamber, a device for engaging the thread in its passage through the chamber, a support for said device mounted for pivotal movement to carry said device from operating position into position for threading and also for sliding movement in the direction of its pivotal axis, and devices for holding said support angularly in position arranged to be moved relatively into and out of cooperative relation by the sliding movement of said support.
11. A thread waxing device for sewing machines having, in combination, a thread waxing chamber, a device for engaging the thread in its passage through the chamber, a support for said device mounted for pivotal movement to carry said device from operating position into position for threading and also for sliding movement in the direction of its pivotal axis, and devices for holding said support respectively in operating and in threading position arranged to be moved relatively into and out of cooperative relation by the sliding movement of said support.
12. A thread waxing device for sewing machines having, in combination, a thread waxing chamber, a device for engaging the thread in its passage through the chamber, a support for said device mounted for pivotal movement to carry said device from operating position into position for threading and for sliding movement in the direction of its pivotal axis, a spring acting upon said support and tending to slide the same axially, a member having a retaining surface, and a projection carried by said support for engagement with said retaining surface to hold the support in position arranged to be held in cooperative relation to said surface by the action of said spring, and to be carried out of cooperative relation to said surface by sliding said support axially against the action of said spring.
13. A thread waxing device for sewing machines having, in combination, a thread waxing chamber, a holder having a passageway, the lower end of which communicates with said chamber and is arranged to be closed by the wax in said chamber, said holder being constructed and arranged to receive a wax containing carton closed at its upper end and open at its lower end so as to discharge into said passageway and to hold said carton so that it will have an air-tight connection with said holder to insure that air will be admitted into the passageway and carton only through the lower end of the passageway.
14. A thread waxing device for sewing machines having, in combination, a thread waxing chamber, a holder having a recess and a passageway leading therefrom, the lower end of which communicates with said chamber and is arranged to be closed by the wax in said chamber, a wax containing carton closed at its upper end and open at its lower end mounted in the recess in said holder so as to discharge into said passageway, a shoulder formed on said holder arranged to be engaged by the lower end of said carton, and a retaining device for said carton acting when moved into retaining position to force the lower end of the carton against said shoulder to form an air-tight joint so that air may be admitted to said passageway and carton only through the lower end of the passageway.
15. A thread waxing device for sewing machines having, in combination, a thread waxing chamber, a holder, adapted to detachably receive a wax containing carton so as to provide a wax supply reservoir, and means for mutilating said carton before it is removed from the holder.
16. A thread waxing device for sewing machines having, in combination, a thread waxing chamber, a holder adapted to detachably receive a wax containing carton so as to provide a wax supply reservoir, means for mutilating said carton, and means for preventing the removal of the carton from the holder until it is mutilated.
17. A thread waxing device for sewing machines having, in combination, a thread waxing chamber, a holder adapted to detachably receive a wax containing carton so as to provide a wax supply reservoir, a retaining device for preventing the removal of the carton from the holder, means for

- latching said retaining device in retaining position, a punch for puncturing the carton, and common means for releasing the latch and actuating the punch arranged to project 5 the punch through the carton before the latch is released.
18. A thread waxing device for sewing machines having, in combination, a thread waxing chamber, a holder adapted to 10 detachably receive a wax containing carton so as to provide a wax supply reservoir, a device for mutilating the carton, and means for actuating said device first to mutilate the carton and then to lift the carton out of operating position.
19. A thread waxing device for sewing machines having, in combination, a thread waxing chamber, a holder adapted to detachably receive a wax containing carton so 15 as to provide a wax supply reservoir, a retaining device for preventing the removal of a carton from the holder, means for latching said retaining device in retaining position, a latch releasing member, a punch, and an actuating member arranged during the 20 continued movement of said member in one direction, first to project the punch through the carton, then to actuate the latch releasing member to release the latch, and finally to move the punch to raise the carton out 30 of operating position with relation to the holder.
20. A thread waxing device for sewing machines having, in combination, a thread waxing chamber, thread guiding devices removably supported therein, and a barometric feeding reservoir for supplying wax to the waxing chamber.
21. A thread waxing device for sewing machines having, in combination, a thread waxing chamber, a reservoir for supplying wax thereto, thread guiding devices within the chamber, and means for maintaining the wax in the chamber in a melted condition and for liquefying the wax in the reservoir 40 sufficiently to enable it to flow into the chamber.
22. A thread waxing device for sewing machines having, in combination, a thread waxing chamber comprising an open receptacle, thread guiding devices within the chamber, and a barometric feeding reservoir connected with the receptacle for supplying wax thereto.

FREDERIC E. BERTRAND.
